UNITED STATES PATENT OFFICE

WALTER PRUSSING, OF BROOKLYN, NEW YORK

HOPPER

Application filed February 15, 1929. Serial No. 340,115.

This invention relates to hoppers and particularly, to the means for feeding blanks of uniform size and shape for further operation thereon. My invention contemplates the provision of extremely simple means for feeding slugs or blanks in succession, in which means the usual agitators have been entirely eliminated.

The various objects of my invention will 10 be clear from the description which follows and from the drawings, in which,

Fig. 1 is a front view of a machine, such as a press, to which my improved feeding means has been applied.

Fig. 2 is a vertical section of part of the hopper and of part of the feed tube or chute which constitute the major part of my improved device.

Fig. 3 is a front view of another form of 20 my improved feeding means adapted for use with light slugs which may not be properly fed by gravity alone.

Fig. 4 is a vertical section of a part thereof, showing the auxiliary feeding means.

Fig. 5 is a horizontal section of the same, taken on the line 5—5 of Fig. 4.

Fig. 6 is a horizontal section of the feeding tube shown in Fig. 4, and

Fig. 7 is a perspective view of one of the 30 slugs or blanks adapted to be fed by my improved device.

In that practical embodiment of my invention which I have shown herein by way of example, as applied to an extruding press, such as for instance, a press used for extruding soft metal slugs into caps for collapsible tubes, I provide a hopper as 10 and a feed tube as 11, which are relatively reciprocated.

By so relatively moving the hopper and 40 the feed tube or chute, the slugs in the hopper are agitated to a minimum extent, without the use of extraneous agitating means, and with a minimum amount of rubbing or abrasive action between the slugs, so that 45 the slugs fed by my mechanism maintain substantially their pristine cleanliness with resulting advantages when the slugs are extruded.

As illustrated in Fig. 1, the hopper 10 is 50 reciprocated by any suitable means, such as

by the attachment thereof to the cross head 12 of an extruding press, as by means of the bolts 13. The cross head is reciprocated in the usual manner by suitable mechanism well-known in the art, and I have shown for 55 this purpose, the crank 14 mounted on the shaft 15, which is rotated by suitable well-known mechanism which need not be shown, said crank 14 being pivotally connected to the upper end of the cross head 12.

For allowing slugs to be dumped in quantities, quickly and easily into the hopper 10, the upper end thereof is left entirely open. The bottom 16, however, of the hopper, is preferably inclined downwardly and terminates in a suitable bearing member as 17, having an opening therein into which the upper end of the tube 11 is inserted, so that when the hopper is reciprocated, it slides over the relatively stationary feed tube 11.

Said tube may take various forms as shown in Figs. 1, 2, 5 and 6. In the form shown in Figs. 1 and 2, for example, the feed tube may be in the form of a cylindrical pipe having a slot as 18 therein, through which the slugs 19, piled in the inside of the tube, are visible, and through which slot a suitable tool may be inserted to straighten out the slugs, should any assume the wrong position or otherwise become jammed in the inside of the tube. 75 The upper end 20 of the feed tube is preferably bevelled as at 21 to terminate a comparatively sharp edge as 22. While the bevel is shown in Fig. 2 as extending from the inner surface of the tube toward the outer surface, it will be understood that the bevel may be reversed, and may then be inclined from the outer face of the tube toward the inner face, it being my invention to reduce the thickness of the tube at its upper end to a 80 minimum, so as to provide as little material at that point as possible against which the slugs in the hopper may impinge and be diverted without entering the interior of the feed tube.

The lower end of said tube may be curved in any suitable manner as illustrated in Fig. 3 to present one slug at a time to the mechanism for operating thereupon, or a suitable feed mechanism indicated diagrammatically 100

at 23 may be provided for removing one slug at a time from the bottom of the pile and feeding the slug to the dies for operating thereon.

Referring now to Figs. 3 to 6 inclusive, I have there shown a feed tube 24 in which the interior opening or chamber is made substantially rectangular in cross-section for the purpose of feeding the tubes in a row with the cylindrical edges thereof in contact instead of in a pile with the flat surfaces 46 thereof in contact. The principle of operation, however, is precisely the same in both cases. As shown in Fig. 5, the passage 25 of the tube 24 is made of the proper shape to receive a slug 45 only with the faces 46 thereof in a substantially vertical position, so that the adjacent slugs 45 in the row are arranged in the tube with their cylindrical surfaces 26 in contact.

I have also shown means for insuring the movement of the slugs through the passage 25, which is particularly useful where the slugs are too light in weight to be fed with certainty by gravity alone. Said means comprises a serrated friction member 30 held to the cam plate 32 as by means of the pins 31 secured at one end to said member and having their other ends inserted into suitable holes in said plate for providing a yielding connection between the plate and the member. Said plate is slotted by the cam slots 33, whereby reciprocation of the plate gives both a longitudinal and a lateral movement to member 30, toward and from the row of slugs.

The plate 32 is slidably supported in the extension 34 of the stationary feed pipe 24, and is guided in its movement by the pins 35 passing through the slots 33. A spring as 36 connected to the stationary lug 37 at one end, and to the lower end of the plate 32 at its other end, serves to return the plate 32 to its uppermost position after it has been pushed down by the lug 38 projecting from the hopper 10 on the descent of said hopper and the later ascent thereof to release the plate. A suitable spring as 39 secured to the plate 32 as at 40 and engaging the member 30 serves to take up any undue pressure which the plate 32 might exert on the member 30, and to provide a yielding connection therebetween.

As has been pointed out hereinbefore, the feed pipe 24 may be curved at its lower end 41 to lead to a suitable feed mechanism 23, including a feed cylinder 42 into which the slugs may be properly piled as by the reciprocating spring plunger 43.

The operation of my improved mechanism is as follows:

As applied to the press illustrated, the crank shaft 15 being rotated and thereby reciprocating the cross head 12 through the intermediary of the crank 14, the hopper 10 is

reciprocated up and down on the end of the stationary feed tube 11. A quantity of slugs having previously been supplied to the hopper, the slugs automatically fall into the end of the tube and are fed therethrough by gravity, or by gravity with the aid of the auxiliary feeding mechanism, to the point where they are to be extruded.

The length of the reciprocatory stroke of the hopper is preferably such that in the uppermost position of the hopper, the edge 22 of the feed tube is a considerable distance below the top of the opening in the bearing 17 of the bottom of the hopper. This allows the slugs which have previously been thrown by the tube over on to the inclined face of the bottom 16, to slide down toward the bearing opening and into the tube. The edge 22 being relatively sharp, offers little or no obstruction to the slugs as they tend to enter the top of the feed tube.

On the downward reciprocatory stroke of the hopper, the tube passes completely through the bearing 17 and into the interior of the hopper to any extent which may be found desirable. As the tube enters the hopper, the slugs which have accumulated about the upper end of the hole in the bearing without falling into said hole are pushed aside by the tube, as are the slugs which have accumulated near the rear face of the hopper. These slugs are pushed upwardly and toward the upper end of the inclined bottom 16 which leads the slugs into the tube in the manner hereinbefore described, the inclined end of the tube aiding the agitating and feeding operation.

By reason of the relative reciprocation of the hopper and the tube, none of the agitating devices normally employed to prevent accumulation of slugs or blanks at an inaccessible point, become necessary, dependence being had entirely upon the minimum agitation of the slugs by the tube on the movement of the hopper to feed the slugs.

In the form illustrated in Figs. 3, 4 and 5, the passage 25 of the tube 24 is so designed that the slugs must enter the tube in the positions shown in Fig. 4. Since this form of my improved device is adapted to feed slugs or blanks made of light weight material such as aluminum, the auxiliary forwarding means illustrated is preferably employed.

On the downward movement of the hopper 10, the lug 38 strikes the upper end of the cam plate 32, moving said cam plate downwardly in the support 34 and at the same time, inwardly, due to the engagement of the pin 35 with the edges of the slot 33. The serrated member 30 is carried down with the plate 32 and also given an inward movement toward the slugs or blanks 45, causing said member to engage the blanks and when the pin 35 reaches the straight part of the slot 33, it

causes said member 30 to carry or push the slugs downwardly in the passage 25.

On the upward movement of the hopper 10, the plate 32 is released, allowing the spring 36 to reverse the movement and allowing the member 30 to release the slugs. The spring 39 forming a yieldable connection between the plate 32 and the member 30, prevents injury to the parts or to the slugs 45 under the pressure exerted thereon when the plate 32 moves toward said slugs.

It will be seen that I have provided an efficient, simple and economical mechanism for continuously feeding blanks in an aligned row from a hopper to which said blanks are indiscriminately supplied in quantities, that the blanks or slugs are agitated to a minimum extent by my improved mechanism, thereby preventing the coating of said blanks with grease or metallic dust particles, and that my improved mechanism is well adapted for the purposes for which it is intended.

I do not wish to be understood as limiting myself in any way to the precise mechanism shown and described but intend to claim my invention as broadly as may be permitted by the state of the prior art and the terms of the appended claims.

I claim:

1. In an automatic feeding mechanism for disc blanks, an open end hopper, a feed tube inserted thereinto, and having a longitudinal slot therein for exposing part of the blanks to view, means for reciprocating the hopper on the upper end of the tube, and means carried by the tube for advancing the blanks in the tube, including a spring pulled slide movable longitudinally of the tube.

2. In an automatic feeding mechanism, a reciprocatory hopper and a stationary feed tube over which the hopper is longitudinally movable, and means operated by the hopper for advancing blanks in the tube.

3. In an automatic feeding mechanism, a hopper, a tube having a longitudinal slot therein inserted into the hopper, and means for relatively reciprocating the hopper and the tube whereby blanks drop into the inside of the tube from the hopper and are accessible through the slot.

4. The combination with a reciprocatory cross-head of a press for extruding blanks into caps for collapsible tubes, of a hopper, a longitudinally slotted feed tube for continuously delivering aligned blanks inserted into the hopper in succession to extruding position in the press, and means for relatively reciprocating the tube and the hopper to cause the tube to enter and leave the interior of the hopper alternately.

5. The combination with an extruding press having a reciprocating cross-head, of a feed tube terminating at its upper end in a relatively sharp edge, and a hopper carried

by the cross-head to reciprocate on the upper end of the tube.

6. The combination with the reciprocatory cross-head of an extruding press, of a hopper carried by the cross-head and a feed tube inserted into the hopper, the upper end of said tube terminating in a relatively sharp edge inclined at an oblique angle to the axis of the tube.

7. In an extruding press of the character described, a cross-head, a feeding device comprising a stationary slotted feed tube terminating in an edge inclined at an oblique angle to the axis of the tube, and a reciprocatory hopper mounted on the upper end of the tube and carried by the cross-head and provided with an otherwise closed bottom having an opening therein for the reception of said tube.

8. In an extruding press of the character described, a reciprocatory cross-head, a stationary slotted feed tube, a hopper mounted on the end of said tube for reciprocation thereon and carried by the cross-head, means for reciprocating said cross-head, and a bottom on said hopper having an opening therein for the passage of said tube.

9. In a feeding device of the character described, a stationary feed tube having a straight portion for continuously delivering blanks in an aligned row to a predetermined point, a hopper into the lower end of which part of the straight portion of said tube is inserted, means for reciprocating the hopper about the inserted end of the tube, and means associated with the tube and operated by the hopper for engaging and advancing the blanks in the tube.

10. In a feeding device for feeding solid disc blanks, a feed tube, a relatively reciprocatory hopper, and reciprocatory means carried by the tube for engaging the outer cylindrical edges of the blanks and for advancing the blanks within the tube.

11. The combination of a tube for feeding blanks, a yieldable member for engaging the outermost surface of, and advancing, blanks within the tube, and means for moving said member radially inwardly of the tube and downwardly to feed blanks, and in the reverse direction alternately.

12. The combination of a tube for feeding solid disc blanks, and a yieldable reciprocatory member for engaging the cylindrical edges of the blanks and advancing the blanks within the tube, a movable hopper into which the tube is inserted, and means for operatively connecting the member with the hopper.

13. In a feeding mechanism of the character described, a hopper, a feed tube inserted thereinto, means for relatively reciprocating the tube and the hopper, a spring-pulled cam plate carried by the tube, and a blank engaging member carried by the plate and yieldable relatively thereto and adapted to be projected through an opening in the tube into

engagement with the blanks in the tube, said plate and member being reciprocated longitudinally and laterally on the relative movement of the hopper and the tube.

14. In a feeding mechanism of the character described, a hopper, a slotted feed tube having its upper end at an oblique angle to the axis of the tube and inserted into the hopper, means for relatively reciprocating the hopper and the tube, comprising a reciprocating cross-head carrying the hopper, and means operated by the hopper for engaging and advancing the blanks in the tube.
